To all whom it may concern:

Be it known that I, Joseph Henschel, a citizen of the United States of America, residing in Manhattan, county of New York, and State of New York, have invented a new, original, and ornamental Design for a Coat, of which the following is a specification, reference being had to the accompanying drawing, forming part thereof, wherein,

Figure 1 is a front view of a coat showing my new design.

The characteristic feature of my design resides in the combination on the coat as shown, of the shaped gored sleeves, and the gored skirt portion, which gored portion commences from either side of the front central panel, and continues around, in gored formation, to either side of the rear central panel, as shown.

I claim:

The ornamental design for a coat, substantially as shown and described.
